SCREEN CLOTH

John J. Grebe, Midland, Mich., assignor to Ewing Development Company, Bay City, Mich., a corporation of Michigan

Application November 21, 1935, Serial No. 50,879

6 Claims. (Cl. 245—8)

This invention relates to an improved screen cloth adapted to be used particularly on the windows of dwellings, offices, etc.

It is the principal object of the invention to provide an article of manufacture which will perform the function of an ordinary window screen cloth, i. e. to prevent the ingress of insects, and which will also be capable of functioning in such manner as to exclude the direct rays of the sun 10 from the interior of a building.

It is another object of the invention to provide an improved window screen cloth which will admit of materially greater vision than does the present commercial screening.

To the accomplishment of the foregoing and related ends, the invention, then, consists in the manufacture hereinafter fully described and particularly pointed out in the claims, the annexed drawing and the following description setting forth in detail certain means for carrying out the invention, such described means illustrating, however, but several of the various ways in which the principle of the invention may be used.

In said annexed drawing:

Figure 1 is a front elevation of a section of one form of my improved screen cloth; Figure 2 is a side elevation of the screen section shown in Figure 1; and, Figure 3 is an end elevation, looking up, of the screen section shown in Figure 1.

Figure 4 is a front elevation of a section showing a modified form of my invention; Figure 5 is a side elevation of the screen cloth section shown in Figure 4; and, Figure 6 is an end elevation, looking up, of the screen section shown in Figure 4.

My improved screen cloth comprises, essentially, spaced, substantially parallel, vertically extending members which may be of circular or other desirable shape in cross section, and spaced, 40 substantially parallel, horizontally extending members having an elongated cross section, the major surfaces whereof are inclined to the plane of the screen, normally being perpendicular thereto, but may be inclined downwardly and outwardly from such perpendicular at any angle thereto up to about 45°. The cross section of the horizontal members is preferably ribbon-like, although it may be rectangular, with rounded corners, or slightly oval in shape.

As illustrated in Figures 1, 2, and 3, the vertically extending members 7 are substantially parallel and regularly spaced apart a distance between about 0.0625 and 0.125 inch. In these figures the vertical members are illustrated as round wires, and in practice I prefer to use wires be-

tween about 0.007 and about 0.015 inch in diameter. Carried between said wires 7 are crimped ribbons so arranged that the horizontal portions 8 thereof are all parallel to each other. The distance between adjacent horizontal members is 5 between about 0.040 and about 0.100 inch. Preferably this distance is about 0.050 inch. The ribbons constituting the horizontal members for this screen section are made by crimping a flat strip of metal, preferably between about 0.002 and 10 about 0.005 inch in thickness by 0.025 to 0.10 inch in width, to form a member provided with substantially parallel sections 8 about 0.0625 inch in length, and substantially parallel sections 9 about 0.050 inch in length, connecting said first 15 portions, the two sections being at right angles to each other. These crimped members are then placed between the vertical wires 7 and permanently fixed thereto by hot tinning or galvanizing. In the event that it is desirable to use flat ribbons 20 as vertical members they are preferably of the same dimensions in cross section as the ribbons employed to form the horizontal members of this screen section. Such flat vertical members would, of course, be incorporated into the screen 25 cloth with their major surfaces perpendicular to the plane of the screen.

In Figures 4, 5, and 6 the horizontal members 10 are flat ribbon-like metal strips extending the entire width of the screen section. The dimensions of such strips in cross-section lie within those given above for the horizontal sections 8 of the crimped ribbons referred to in Figures 1-3 inclusive. These members 10 are substantially parallel and regularly spaced apart the same distances as the horizontal portions 8 of said crimped ribbon. These members 10 are held in position by spaced substantially parallel vertical members each comprising two strands of wire 11 and 12 which preferably cross each other between 35 each horizontal member 10.

When the plane of the major surfaces of the horizontal members in my new screen cloth is substantially perpendicular to the plane of the screen, such cloth is particularly adapted to be 45 used on screen frames set in windows with a southern exposure. I prefer to use on windows having an east or west exposure, or on the upper floors of tall buildings, a screen cloth in which the ratio of the thickness of the screen to the distance the horizontal members are spaced apart is preferably below 1 to 1, or in which the plane of the major surfaces of the horizontal members in the screen is inclined down and outward at 50 55

an angle of up to 45° from the perpendicular to the plane of the screen.

The effect of my novel screen cloth in usage is to reflect and absorb the direct rays of the sun, thereby excluding such rays from the interior. To increase the absorption of the rays of the sun, my screen cloth is preferably given a black etched finish. This may be done, for example, by treating the tinned surface of my screen section with 10 hydrogen sulphide fumes.

The ratio of the thickness of my improved screen to the vertical distance between the horizontal members thereof is preferably not less than 1 to 2 and preferably not more than 2 to 1. This 15 is an essential requirement, because if the thickness of the screen is less than one-half the vertical distance between the horizontal members of the screen, the screen will not function effectively to exclude the rays of the sun, while if the thickness of the screen is materially more than twice the vertical width of the openings therein, the degree of vision is lessened to an undesirable point when it is desired to see therethrough at somewhat of an angle to the perpendicular from the 20 vertical plane of the screen as normally used. While screens of the type and form hereinbefore described can be made with spacing between the horizontal members less than the dimensions above given, such are generally undesirable, because of diffraction effects which cause images to be blurred through the screen so that a person 25 looking therethrough sees two or more outlines of the same object.

In practice, I have determined that the per cent open area for vision in the plane of the major surfaces of the horizontal members of my screen cloth is approximately 95 per cent, while the open area for vision in ordinary commercial screening is only about 75 per cent.

Other modes of applying the principle of my invention may be employed instead of those explained, change being made as regards the manufacture herein disclosed, provided the means stated by any of the following claims or the equivalent of such stated means be employed.

I therefore particularly point out and distinctly claim as my invention:

1. In an insect screen capable of substantially excluding the passage therethrough of direct sunlight, fixed substantially parallel members having an elongated cross-section throughout their length, spaced apart less than about 0.10 inch, the major surfaces of said members being inclined to the plane of the screen, said members

being spaced apart less than twice the width thereof.

2. In an insect screen capable of substantially excluding the passage therethrough of direct sunlight, fixed substantially parallel horizontally extending members having an elongated cross-section throughout their length spaced apart between about 0.04 and about 0.10 inch, the major surfaces of said horizontal members being inclined to the plane of the screen at an angle up to about 45° from the perpendicular to said plane, said members being spaced apart less than twice the width of the horizontal members.

3. In an insect screen capable of substantially excluding the passage therethrough of direct sunlight, fixed substantially parallel members having an elongated cross-section throughout their length, spaced apart less than about 0.10 inch, the major surfaces of said members being inclined to the plane of the screen, said members being spaced apart a distance not materially greater than the width thereof.

4. In an insect screen capable of substantially excluding the passage therethrough of direct sunlight, fixed substantially parallel horizontally extending members having an elongated cross-section throughout their length, spaced apart between about 0.04 and about 0.10 inch, the major surfaces of said horizontal members being inclined to the plane of the screen at an angle up to about 45° from the perpendicular to said plane, said members being spaced apart a distance not materially greater than the width of the horizontal members.

5. In an insect screen capable of substantially excluding the passage therethrough of direct sunlight, fixed substantially parallel members having an elongated cross-section throughout their length, spaced apart between about 0.04 and about 0.10 inch, the major surfaces of said members being in a plane approximately perpendicular to the plane of the screen, said members being spaced apart less than twice the width thereof.

6. In an insect screen capable of substantially excluding the passage therethrough of direct sunlight, fixed substantially parallel members having an elongated cross-section throughout their length, spaced apart less than about 0.10 inch, the major surfaces of said members being inclined to the plane of the screen at an angle up to about 45° from the perpendicular to said plane, said members being spaced apart a distance not materially greater than the width thereof.

JOHN J. GREBE.
